UNITED STATES PATENT OFFICE.

CHARLES GRANDISON CHAMBERLAIN, OF PACIFIC GROVE, CALIFORNIA,
ASSIGNOR OF ONE-HALF TO J. H. PLUMB AND J. S. METTEER, OF SAME
PLACE.

RAIL-FASTENER.

SPECIFICATION forming part of Letters Patent No. 552,098, dated December 31, 1895.

Application filed May 28, 1895. Serial No. 550,987. (No model.)

To all whom it may concern:

Be it known that I, CHARLES GRANDISON CHAMBERLAIN, a citizen of the United States, residing at Pacific Grove, in the county of 5 Monterey and State of California, have invented a new and useful Rail-Fastener, of which the following is a specification.

This invention relates to an improvement in railway chairs or fasteners, and has for its 10 object to provide a simple and efficient construction of rail-chair which is capable of embracing the base-flange of the rail upon both sides, and also bearing against the opposite sides of the web, whereby the rail is 15 firmly clamped and supported and effectively held both vertically and laterally.

The invention consists in a chair adapted to pass beneath and underlie the base of a rail, forming a support therefor, said chair being 20 provided with a pair of diagonally-disposed lugs for embracing and clamping the base of the rail and adapted also to bear against the web of the rail at opposite sides, said chair being further provided with elongated 25 openings or slots arranged opposite to the inwardly-extending points of said lugs and in line with the opposite edges of the base of the rail when in operative position, said slots being adapted to receive tapering spikes, 30 which, when driven into place, will serve to swing the chair sufficiently to cause the same to still more firmly clamp the base of the rail.

In the accompanying drawings, Figure 1 is a perspective view of a railway chair or fastener constructed in accordance with this 35 invention. Fig. 2 is a plan view of the same. Fig. 3 is a longitudinal vertical section taken through one of my improved chairs in line with the slot therein, showing also a rail and 40 a portion of a tie in section. Fig. 4 is a plan view of a portion of a road-bed with my improved chair applied. Fig. 5 is a detail perspective view of one of the improved coupling-plates.

Similar numerals of reference designate corresponding parts in the several figures of the drawings.

Considerable difficulty has been experienced in the use of rail-chairs, as heretofore constructed, in that as they are slipped loosely on the end of the rail more or less motion or

play is permitted between the rail and the chair, which has given rise to the disagreeable and continuous rattling during the passage of trains. By means of this invention 55 all motion or play between the rail and chair is effectively overcome by reason of the chair closely embracing and clamping the bottom edges and upper face of the base of the rail. The improved chair, which will now be described, also serves as a thorough brace against any tendency to overturn the rail, caused by centrifugal force on curves or lateral motion on straight lines, by clamping the base of the rail on both sides and by arranging 65 the points of the lugs so that they will reach well up and bear against the web of the rail upon opposite sides.

Referring to the accompanying drawings, the improved rail-chair comprises a substantially flat base or bearing plate 1, which is interposed between the base of the rail and the upper face of the tie and serves as an effective support for the rail, preventing the latter from wearing into a wooden tie. The 75 base 1 is provided with a pair of upwardly and inwardly projecting lugs 2, which are arranged at or near the opposite side edges of the base and are therefore diagonally disposed, as shown. The outer opposite faces of the lugs 80 2 are arranged in the plane of the opposite side edges of the base 1, and the inner adjacent edges of said lugs are inclined and extend in parallel relation, thereby forming an oblique or diagonal recess or space of a width sufficient 85 to receive the base of the rail when the chair is turned into such position as to bring said oblique or diagonal recess into alignment with the base of the rail.

It is to be understood that the lugs 2 are 90 formed in such manner that their bearing faces will correspond exactly to the shape of the base of the rail and so that the points of said lugs will bear snugly against and firmly support the web of the rail, as indicated in 95 Fig. 3. For this reason said lugs are varied in shape according to the particular shape or weight of the rail to be used in the construction of the road-bed.

3 designates a pair of elongated openings 100 or slots. These slots are also diagonally disposed and are located one opposite the point

of each lug 2 and in line with the edge of the base of the rail when in operative position. The slots 3 are elongated longitudinally of the chair and are of a length sufficient to extend slightly beneath the adjacent edge of the base of the rail.

4 designates a spike, which is formed with a pointed and tapering shank, as shown, and provided with the usual head for engaging the base of the rail. After the chair has been placed beneath the rail and turned so as to bring the lugs thereof into engagement with said rail, a pair of these tapering spikes are inserted into and driven downward through the slots 3, the effect of which is to still further swing the chair and cause the lugs thereof to bind against the base and web of the rail. It will be understood that this is caused by the tapering sides of the spikes bearing against the edges of the base of the rail and the outer walls or ends of the slots or openings 3. When the spikes have been driven home, the heads thereof will engage the base-flanges of the rail, thereby assisting in anchoring the rail and serving to effectually prevent the chair from turning in a manner that will be readily understood.

From the foregoing description it will be apparent that the improved chair is placed in position by introducing the same between adjacent ties and beneath the rail with the oblique or diagonal recess between the lugs in line with said rail, and lowering the rail until it rests upon the flat base of the chair 1. The chair is then turned until the lugs thereof closely embrace and bind against the base and web of the rail, after which the tapering spikes are driven home in the manner above described. It will be apparent that as the train passes over the rails, the weight thereof is thrown upon said chairs and serves to hold them in place. There is consequently no vertical strain on the spikes as in the usual construction, the strain being in a lateral direction, which the spikes are perfectly capable of withstanding many times over. By the use of these chairs the ties are also protected from cutting by the rails and will last considerably longer as a result. It is to be understood, also, that the chairs may be made in rights and lefts, as illustrated in Fig. 4, and these may be alternated or arranged in any manner which is found by practice to be the most serviceable.

5 designates a coupling-plate intended as a substitute for the ordinary fish-plate. This plate is formed from sheet iron or steel, and is

made of a length greater than the distance between two adjacent ties, so as to slightly overlap the latter. The plate 5 is provided with two spurs or projections 6, one near each end, 60 formed integrally therewith and adapted to engage notches formed in the under side of the head of the rails, as shown. Two of such coupling-plates 5 are employed at the meeting ends of adjacent rails, as shown in Fig. 4, said 65 plates conforming in shape to the head, web, and base of the rail so as to fit snugly against the same. It will be understood, that by reason of the spurs or projections 6 engaging positively with the notched ends of the rails, 70 when the chairs 1 are applied and brought to bear against the coupling-plates, the latter are held as effectually as if bolted to the rail and are not so liable to get loose. These plates may be manufactured at very low cost and are 75 more easily applied than the ordinary fish-plates.

It will be apparent that changes in the form and proportion of the base and diagonally-disposed lugs and in the exact length and location of the elongated openings or slots, and the minor details of construction may be resorted to without departing from the spirit or sacrificing any of the advantages of this invention. 85

Having thus described the invention, what is claimed as new, and desired to be secured by Letters Patent, is—

The herein described railway chair, comprising a substantially rectangular base plate 90 adapted to be interposed between the base of a rail and a tie, a pair of diagonally disposed lugs formed to embrace and bear against the base flange and head and web of the rail and arranged in such manner as to permit the 95 chair to be introduced beneath the rail, and a pair of elongated openings or slots also diagonally disposed and arranged one opposite each lug and in line with the opposite edges of the base of the rail, said openings or slots 100 being extended beneath the base of the rail and adapted to receive tapering spikes whereby the driving of a spike will serve to tightly lock the rail within the chair, substantially as described. 105

In testimony that I claim the foregoing as my own I have hereto affixed my signature in the presence of two witnesses.

CHARLES GRANDISON CHAMBERLAIN.
